UNITED STATES PATENT OFFICE.

CHARLES A. LINDSTROM, OF PITTSBURGH, PENNSYLVANIA; THE UNION TRUST COMPANY OF PITTSBURGH EXECUTOR OF THE ESTATE OF SAID CHARLES A. LINDSTROM, DECEASED.

DISCHARGE-VALVE ARRANGEMENT FOR TRANSPORTATION TANKS.

Application filed January 31, 1921. Serial No. 441,262.

To all whom it may concern:

Be it known that I, CHARLES A. LINDSTROM, a citizen of the United States, residing at Pittsburgh, in the county of Allegheny and State of Pennsylvania, have invented a new and useful Improvement in Discharge-Valve Arrangements for Transportation Tanks, of which the following is a full, clear, and exact description, reference being had to the accompanying drawings, forming part of this specification, in which—

Figure 1 is a partial longitudinal vertical section of a tank car, showing one form of my invention applied thereto;

Figure 2 is a detail view showing a vertical section of the parts at the upper part of Figure 1 but in a different position;

Figures 3 and 4 are vertical longitudinal sections of a portion of a tank showing two other embodiments;

Figure 5 is a detail view of certain of the parts;

Figure 6 is a view similar to Figure 1, but showing a further modification;

Figure 7 is a detail view partly in plan and partly in horizontal section, of some of the parts shown in Figure 6; and

Figure 8 is a perspective view of the lever 30 and cam of Figure 6.

My invention has relation to discharge valve devices or arrangements for transportation tanks such as are used in transporting oils or other liquids and which are provided with a bottom discharge opening.

In the use of tank cars of the character above described, the shape of the tanks frequently become very considerably distorted owing to injuries received in service and also from the strains caused by the weight of the tanks and their contents. The result of this is that the proper relations between the length of the upwardly extending stems of the valves and the diameter of the tanks is not maintained, which interferes with the proper operation and seating of the valves.

One object of my invention is to provide means of simple and efficient character which will automatically compensate for changes in the rotundity of the tanks and permit of proper operation of the valves regardless of such changes.

Another object of my invention is to provide means of simple and efficient character which will permit the valve to readily adjust itself to the valve seat without affecting the stem or interfering with the proper operation of the parts.

A further object of my invention is to provide a "telltale" device which will be operated by the movement of the valve or its stem for the purpose of indicating whether or not the valves are properly seated. This telltale device may also take the form of means which will act to positively prevent the seating of the cover over the hole in the dome, through which the valve is operated until the valve is closed.

A still further object of my invention is to provide a construction and arrangement of this character which will be simple in its construction and not liable to get out of order in service and in which the valve may readily be detached and removed.

The nature of my invention will be best understood by reference to the accompanying drawings in which I have shown several different embodiments of it and which will now be described, it being premised, however, that the embodiments shown are illustrative only and that various modifications may be made in the construction, arrangement and combination of the parts without departing from the spirit and scope of my invention as defined in the appended claims.

In the form of my invention shown in Figures 1 and 2, the reference character 2 designates the tank of a transportation car of any usual or suitable construction and which is provided with a dome 3 having the dome head 4 and the removable top closure 20. The tank is provided with a bottom discharge spout arrangement which is preferably of the form described and claimed in my Patent No. 1,335,445, dated March 30, 1920. A valve 6 is connected to the lower portion 7 of a two-part stem 7 and 8 by a quick detachable connection of some suitable character. This connection may consist in providing the lower end of the stem section 7 with a head or button 9, convex on its under side and adapted to fit within the concave bottom portion of a seat 10 on the valve, being secured to the latter by a removable U shaped key 11, shown in sec-

tion in Figure 1. The two sections 7 and 8 of the valve stem are united by a slip joint or slip bearing as indicated at 12, the joint forming portions of the two sections having 5 a vertically slideable connection with each other, but being so shaped in cross section that the two sections will rotate as a unit. The valve is normally held to its seat by means of a spring 13 which surrounds 10 the valve stem and is seated at its lower end upon a shoulder 14 on the lower portion 7 of the stem and bears at its upper end against an extension 15^a of a bracket 15. The valve stem section 7 has a screw thread 15 16 which cooperates with the internally threaded head 17 of the bracket 15 whereby when the valve stem is turned in the proper direction the valve is unseated. Mounted on the upper end of the valve stem section 20 8 is an actuating handle or lever 18.

It will be readily seen that by the provision of the slip joint 12 the main portion of the valve stem is rendered largely independent of the valve proper and that the 25 latter is capable of a considerable vertical movement independent of the section 8 of the stem. This permits flattening or change in the vertical diameter of the tank without disturbing the operative function of the 30 valve rod.

In these figures I have also shown a "tell-tale" device in connection with the valve stem. It is usual in the construction of transportation tanks to locate the valve 35 and valve stem away from the vertical center line of the dome, to give free access to the interior of the tank when the dome cover is removed. This places the valve in a position in which its upper end is readily 40 supported by a bracket, as shown in Figures 1, 2, 3 and 4. The "tell-tale" device is attached to this bracket and consists of a lever 19 pivoted at 19^a and extending across the valve stem to a point beyond the edge of 45 the opening in the dome, as shown in Figures 1 and 3, or near to the opening, as shown in Figure 4. The free end portion of the lever 19 is bent upwardly to a position in which it is normally just clear of the 50 under side of the cover plate. The valve stem is made in two parts and there are two slip joints. The lower one 12 extends upwardly from the shoulder 14 and the upper one is at the upper end portion 21, which 55 is made in angular form and extends through the hub of the actuating handle or lever 18 and is capable of sliding vertically in the hub for the purpose of actuating the "tell-tale" device. By having the pivot 19^a 60 located back of the valve stem and having the lever 19 extending across the valve stem and on towards the dome opening, any lifting movement imparted to the lever 19 by the valve stem will be increased at the free 65 end of the lever. It will be readily seen

that if the valve is not properly seated this fact would be indicated by the lever 19, and also, that the upper end of said lever will act as positive means to prevent the seating of the cover 20 so long as the discharge valve remains unseated. Any difficulty in seating this cover plate will therefore warn the operator that the valve is not properly seated and it will be necessary to close the valve before the cover is fastened down. 70

In the construction shown in Figure 3 the stem 13^a is arranged below the head 17 of the bracket 15 and bears at its lower end against a shoulder 14^a on the lower end of the valve stem and at its upper end against the lower side of the head 17. In this construction the valve stem is made in one piece but its upper end portion 21 is of angular form as in the construction shown in Figures 1 and 2 to provide a slip joint between 80 the upper end of the valve stem and the hub of the operating handle or lever 18. 85

Figure 4 shows a further modification of the invention. In this form the lower section 7^b of the valve stem has a tooth 22 which co-acts with the thread in the head 17^b of the bracket 15. The upper section 8^b of the valve stem is connected to the lower section 7^b by a slip joint 12^b located above the head 17^b. The construction below the head 17^b is like that shown in Figure 3. The valve stem section 8^b is provided at its upper end with an actuating lever or handle 18^b having the slip joint connection 21 with the valve stem and provided with a cam portion 23. This cam portion is so arranged that as the lever is turned to unseat the valve it raises the tell-tale lever 19^b and thereby projects the pin 24 connected to the free end of such lever to a position which will prevent the seating of the cover plate 20^b. 100 105

Figure 6 shows a still further modification which is generally similar to that shown in Figure 4, except that the lower bracket arm has been made in two parts, 15^c and 15^d. Set screws 25 are added to the uprights of the said bracket and the diameter of the shoulder 14^c of the valve stem is increased. The object of making the bracket in two parts is to facilitate the insertion and removal of the stem 7^c with spring 13^c when the spring is located underneath the head of the bracket without 110 115 detaching bracket 15^c from the bottom plate 120 of the tank, the same as can be done in the arrangement shown in Figure 1, with the spring above the head. The object of the set screws 25 is to limit the lift of the valve to a prearranged height, except when it is desired to remove the valve entirely for 125 repairs or renewals. It is well known to those familiar with the art that it is only necessary to lift a valve a comparatively small amount in order to obtain an annular open- 130

ing around the valve which is equal to the area of the opening in which the valve is seated; further, if the valve should be lifted clear out of its seat, difficulties would arise in having it properly seated again without guidance by hand. When raising the valve the required amount for emptying the contents of the tank the shoulder 14° on the stem 7° will come up against the stop screws 25 which will prevent further raising; when, however, it should become necessary to remove the valve entirely the screws 25 are screwed out, permitting the raising of the shoulder 14° to a height sufficient for the valve 6 to clear the seat 10, thus permitting its removal. For this purpose the pitch of the thread 16° should be such that a one-half turn of the stem will be sufficient to lift the valve to give the required area of discharge opening at the valve. For the same purpose, the cam 23° on the hub portion of the actuating handle 18° is made of such shape (see Figure 8) as to give the required lift to the pin 24° by a half turn of the lever 18°, after which the telltale lever 19° will ride idly on the horizontal portion of the cam surface. Similar modifications and additions may be made in the constructions shown in Figures 1 and 3 by inserting a pin through the lower end of the valve stem a sufficient distance below the bottom of head 17 to allow for the required lift of the valve, this pin to be removed when it is desired to remove the valve entirely.

It will, therefore, be obvious that the telltale device, either as a telltale merely, or so arranged to act as a guard, may take various other forms and arrangements than those described. It is also obvious that changes can be made in the form and arrangement of the slip joint, as well as in the construction and character of the valve, its seat and other parts.

The advantages of my invention will be apparent to those familiar with the operation of transportation tanks since it overcomes in a simple, efficient, positive manner the difficulties above referred to; and in its more complete form also insures that the discharge valve shall be properly reseated after each operation thereof.

I claim:

1. The combination with a transportation tank having a bottom discharge opening and provided with a filling dome, of a valve for closing said opening, a valve-operating stem projecting upwardly therefrom, a bracket supporting the upper end of said stem, and a telltale lever operatively supported by said bracket in position to overlie the upper end of said stem and to be operatively engaged thereby, whereby when the stem has been operated to open the valve, the telltale lever will be in raised position, substantially as described.

2. The combination with a transportation tank having a bottom discharge opening and provided with a filling dome, of a valve for closing said opening, a valve-operating stem projecting upwardly therefrom, a bracket supporting the upper end of said stem, and a telltale lever pivotally supported by said bracket in position to overlie the upper end of said stem and to be operatively engaged thereby, whereby when the stem has been operated to open the valve, the telltale lever will be in raised position, substantially as described.

3. The combination with a transportation tank having a bottom discharge opening and provided with a filling dome, of a valve for closing said opening, a valve-operating stem projecting upwardly therefrom, a bracket supporting the upper end of said stem, and a telltale lever operatively supported by said bracket in position to overlie the upper end of said stem and to be operatively engaged thereby, whereby when the stem has been operated to open the valve, the telltale lever will be in raised position, said stem being constructed to permit variations in the length thereof without operating the telltale lever, substantially as described.

4. The combination with a tank car having a bottom discharge opening and provided with a dome, of a lifting valve for controlling said opening, a stem extending upwardly from said valve into the dome, and operating means for said stem slidably secured thereto, said dome having a removable portion, and means actuated by the movement of the valve for preventing the reseating of said removable portion when the valve is in unseated position, substantially as described.

5. The combination with a tank car having a bottom discharge opening and provided with a dome, of a lifting valve for controlling said opening, valve operating means extending upwardly from said valve into the dome and connected to said valve whereby to move the same away from its seat, said dome having a removable portion, means supported independently of but actuated by the valve operating means for preventing the reseating of said removable portion when the valve is in unseated position, and removable means for normally limiting the opening movement of said valve, substantially as described.

6. The combination with a tank car having a bottom discharge opening and provided with a dome, of a lifting valve for controlling said opening, operating means for said valve extending upwardly therefrom into the dome and connected to the valve, said dome having a removable portion, and telltale means pivotally supported in said dome independently of said valve operating means and actuated by the latter

for preventing the reseating of said removable portion when the valve is in unseated position, substantially as described.

7. The combination with a tank car having a bottom discharge opening and provided with a dome, of a lifting valve for controlling said opening, valve-operating means extending upwardly from said valve into the dome, the construction being such that said valve-operating means must be

actuated in order to either unseat or seat the valve, said dome having a removable portion, and means supported independently of but actuated by the valve-operating means for preventing the reseating of said removable portion when the valve is in unseated position.

In testimony whereof, I have hereunto set my hand.

CHARLES A. LINDSTROM.
